CURRENT WHEEL

John M. Morris, Atlanta, Ga.

Application May 17, 1945, Serial No. 594,350

1 Claim. (Cl. 170—110)

1

This invention relates to a wheel adapted to be driven by a current of water or the like and used for driving a dynamo or other machinery.

More particularly, the present invention relates to improvements in current wheels of that type embodying a rotary disc to which are hinged a plurality of blades or paddles so that they may fold in one direction toward and parallel with the disc, and wherein means is provided to stop each blade in a position at right angles to the disc when it is unfolded.

An object of the present invention is to provide a current wheel of the above kind which is comparatively simple in construction, highly efficient in operation, and adapted to be readily and economically manufactured.

The exact nature of the present invention will become apparent from the following description when considered in connection with the accompanying drawings, in which—

Figure 1 is a bottom plan view of a current wheel constructed in accordance with the present invention.

Figure 2 is a vertical section taken on line 2—2 of Figure 1.

Figure 3 is a horizontal section taken on line 3—3 of Figure 2.

Figure 4 is an enlarged fragmentary section taken on line 4—4 of Figure 3.

Figure 5 is a view similar to Figure 4 taken on line 5—5 of Figure 3.

Referring in detail to the drawings, the present current wheel includes a sheet metal disc 5 having a central hub 6 adapted to receive and be secured on a driven shaft 7 which is journaled in a suitable frame or support 8 and adapted to drive a dynamo or other machinery 9.

The wheel further includes a plurality of spoon-shaped sheet metal paddles or blades 10, each having an inner reduced or shank portion 11 40 hinged to one side of the disc 5 adjacent the periphery of the latter, by means of a leaf hinge 12, one leaf of which is riveted or otherwise secured to the shank 11 and the other leaf of which is similarly secured to the disc 5. The blades or paddles are uniformly spaced and radiate from the disc 5, the hinges being disposed so that the blades or paddles may all fold in one direction toward and parallel with the disc 5. The shank 11 of each blade is provided on the side edge ad-

2

jacent the disc 5 with a stop flange 13 that is disposed at right angles to the blade shank and arranged to engage the adjacent surface of the disc 5 so as to stop the blade at right angles to the disc when the blade is unfolded.

The arrangement is such that the blades on one side of the axis of the wheel unfold by the action of the current, while those upon the other side of the axis automatically fold up toward and parallel with the disc. It will be noted that each blade 10 is mounted to turn about an axis coincident with a chord of the disc 5 and so as to incline from the radial in a direction opposite the flow of the current which actuates the wheel, so as to produce a most efficient driving action. Obviously, the wheel may be placed in a stream and employed in propelling machinery. Also, the disc 5 and blades 10 may be readily stamped from sheet metal, and conventional leaf hinges may be employed for assembling the blades to the disc. The wheel is designed for ready and economical quantity production, and most efficient action of the current on the blades is insured because the latter project outwardly beyond the periphery of the disc and are given a shape in the form of the bowl of a spoon.

From the foregoing description, it is believed that the construction, operation and advantages of the present invention will be readily understood and appreciated by those skilled in the art. It will be apparent that the wheel may be driven by any current or by relative movement between the wheel and a liquid or gaseous medium, and regardless of the direction of the current.

I claim:

A current wheel comprising a single disc having a central hub for reception of a driven shaft, a plurality of more than two separate spoon-shaped sheet metal blades radiating from the disc and arranged in uniformly spaced relation, each blade having an inner reduced end portion forming a short flat shank, and a leaf hinge mounting each blade on one face of and adjacent the periphery of the disc to turn about an axis coincident with a chord of the disc, one leaf of each hinge being attached to the shank of the associated blade adjacent one side edge of said shank and the other leaf of the hinge being attached to the disc so that upon folding of the hinges the blades may fold in one direction toward and

parallel with the disc, the blades on one side of the axis of the disc unfolding by the action of the current and those on the other side of said axis automatically folding up toward and parallel with the disc by the action of the current, and a flange on the other side edge of the shank of each blade, said flange being disposed at right angles to the shank so as to flatly butt the adjacent face of the disc when the blade is unfolded.
